DRESS OR SIMILAR ARTICLE

Abraham Goldfarb, Great Neck, N. Y.

Application April 23, 1952, Serial No. 19,447

Term of patent 7 years

(Cl. D3—26)

To all whom it may concern:

Be it known that I, Abraham Goldfarb, a citizen of the United States of America, residing in Great Neck, county of Nassau, and State of New York, have invented a new, original, and ornamental Design for a Dress or Similar Article, of which the following is a specification, reference being had to the accompanying drawing, forming part thereof, wherein,

I claim:

The ornamental design for a dress or similar article, substantially as shown.

ABRAHAM GOLDFARB.
